PORTABLE COMBINED HEATER AND LAMP

Jules A. Court, Palo Alto, Calif., assignor to TC Products, Palo Alto, Calif.

Filed Dec. 9, 1969, Ser. No. 20,424

Term of patent 14 years

Int. Cl. D23—03; D26—02
U.S. Cl. D23—77

FIG. 1 is a perspective view of the portable combined heater and lamp embodying my new design;
FIG. 2 is a side elevational view thereof;
FIG. 3 is an opposite side elevational view thereof;
FIG. 4 is a top plan view thereof;
FIG. 5 is a bottom plan view thereof;
FIG. 6 is a rear elevational view thereof; and
FIG. 7 is a front elevational view thereof.

I claim:

The ornamental design for a portable combined heater and lamp, as shown and described.
